BELT SANDER

Paul O. Rawson, Trumbull, and George L. Schick, New Canaan, Conn., assignors, by mesne assignments, to The Stanley Works, New Britain, Conn., a corporation of Connecticut

Filed Dec. 2, 1964, Ser. No. 82,869

Term of patent 14 years

(Cl. D37—1)

FIG. 1

FIG. 2

FIG. 3

FIG. 4

FIG. 1 is a top plan view of a belt sander embodying our design;

FIG. 2 is a right side elevation view of a belt sander embodying our design as viewed in FIG. 3;

FIG. 3 is a rear elevation view of a belt sander embodying our design; and

FIG. 4 is a left side elevation view of a belt sander embodying our design.

We claim:

The ornamental design for a belt sander, as shown.
